Alfred Hutchinson

United States Patent Office.

ALFRED HUTCHINSON, OF PHILADELPHIA, PENNSYLVANIA.

Design No. 3,610, dated August 10, 1869.

DESIGN FOR THE FRAME OF A SCHOOL-DESK.

The Schedule referred to in these Letters Patent and making part of the same.

To all whom it may concern:

Be it known that I, ALFRED HUTCHINSON, of Philadelphia, county of Philadelphia, State of Pennsylvania, have originated a new Design for the Frame of a School-Desk; and I do hereby declare that the accompanying drawing, and following explanation thereof, form a full, clear, and exact description of the said design.

In the drawing, the figure represents my design for the frame of a school-desk, which consists of the side pieces *a* and *b*, formed at the bottom into feet, *a'* and *b'*, and connected together by an arched cross-piece, *c*, and straight cross-piece *d*.

A lug, *f*, projects from the side piece *b*, and the upper edge *h* of the frame is inclined, as shown.

The inclination of the frame will be understood by viewing it in connection with the base-line *y* and perpendicular line *x*.

I claim the design for the frame of a school-desk, substantially as described, and as represented in and by the accompanying drawing.

In testimony whereof, I have signed my name to this specification, in the presence of two subscribing witnesses.

ALFRED HUTCHINSON.

Witnesses:

E. H. BAILEY,
Wm. A. STEEL.
